CLAMP

Harlin A. Brelsford, Haddon Heights, N. J., assignor to Radio Corporation of America, a corporation of Delaware

Application October 30, 1943, Serial No. 508,423

4 Claims. (Cl. 248—346)

The invention covered herein may be manufactured and used by or for the Government of the United States for any governmental purpose without payment to me or assigns of any royalty thereon.

This invention relates to clamps and particularly to improvements in so-called "tube clamps."

In many mobile electrical installations, and especially in those subject to shocks and tremors of external origin, it is customary to secure certain replaceable units such, for example, as vacuum tubes, coil forms, capacitors, etc. to a chassis or other base by means of adjustable clamps. The usual "tube clamp" comprises a strip of metal affixed to the support and adapted to encircle the base of the tube, or other unit, and is provided at its opposite ends with complementary lugs or ears through which the clamping force is applied to the strip as by means of a screw and nut. The principal objection to such clamps is that the adjusting mechanism (e. g. the screw and nut) is accessible only from the side of the installation. Hence, if, as is usually the case, the tubes and other units are arranged in closely spaced rows the clamps in the center and rear rows are relatively inaccessible so long as the units in the other rows remain in position.

Accordingly, the principal object of the present invention is to provide a simple, inexpensive and trouble-free clamp and one wherein the adjusting mechanism is accessible from the top (or bottom) of the set whereby replacement of the clamped device may be effected without disturbing the set-up of nearby units.

The foregoing and other objects and advantages are achieved, in accordance with the invention, by the combination with a spring metal strip or like part, adapted to encircle the unit to be clamped, of cam means operatively connecting the ends of said strip and an actuating member (say, a screw), which extends in a direction substantially perpendicular to the plane of the surface upon which the assembly is mounted, for applying a clamping force to said unit through said cam means and spring metal strip.

Certain preferred embodiments of the invention are shown in the accompanying drawing, wherein:

Figure 1 is an elevational view of a vacuum tube and a clamp therefor constructed and arranged in accordance with the principle of the invention and showing the direction and manner of applying the clamping force,

Figure 2 is a plan view of the assembly shown in Figure 1, and

Figure 3 is a fragmentary view in perspective showing another embodiment of the invention.

In the drawing, wherein like reference characters designate the same or corresponding parts in all figures, 1 designates a panel or chassis of a radio or other apparatus and 3 designates a device, say a vacuum tube having a cylindrical socket or base 5 and which is supported on or above the panel by a clamp comprising a spring metal strip 7 which encircles the base 5 of the device. As shown in Fig. 3, the spring metal strip 7 may simply rest on the panel 1 or, as shown in Figs. 1 and 2, it may be supported above the panel as on legs 9a, 9b, etc. which are welded or otherwise affixed to the outer surface of the said strip. In this latter case, the feet of the rear legs 9c and 9d may be secured to the panel 1 as by screws 11c and 11d, respectively; the front legs 9a and 9b being free to slide on the surface of the panel so that the spring strip 7 may be flexed when a clamping force, supplied by a screw 13 and nut 15, is applied thereto or removed therefrom. The nut 15 will be understood to be welded or otherwise affixed to the panel 1.

25 The screw 13 extends from a point beneath the panel 1 upwardly between the outwardly turned ends of the spring metal strip 7 and is provided at its upper end with a cam comprising a rigid, inverted V-shape member 17 having a flattened central portion 17f against which the head 13a of the screw 13 is adapted to bear. A projection 13b on the screw beneath the flattened central portion of the cam 17 causes the cam to follow the screw when it is being unscrewed.

30 In the embodiment of the invention shown in Figs. 1 and 2 the outwardly extending portions of the flexible metal strip 7 are provided with cam surfaces 7a and 7b similar to the ones on the screw actuated cam 17. That is to say, the outer-surface sections of the strip 7, adjacent to its opposite ends, slant downwardly and outwardly with respect to a line drawn perpendicular to the base between the said end portions, and at an angle corresponding substantially to the inclined inner surfaces of the inverted V-shape cam 17.

35 Thus, as the screw 13 is turned by means of a screw driver 19 inserted from above, the cam surfaces of the part 17 ride on the inclined surfaces 7a and 7b on the clamping strip 7 and move it into or out of clamping engagement with the base 5 as determined by the direction in which it is rotated. As previously mentioned, the movement of the spring metal strip 7 is in no wise inhibited by the legs 9a and 9b since they are

not attached to the panel 1 but are mounted to permit of slidable movement thereon.

It is not essential that faces 7a and 7b on the spring metal strip 7 have the same angle of tilt as those on the cam 17. In fact, as shown in Fig. 3, the said parts 7a and 7b may comprise parallel faces perpendicular to the plane of the panel 1. In this case, the inclined faces of the cam 17 bear only against the upper edges of these parallel faces when the cam is actuated by the screw 13. While this would appear to cause the upper edge of the strip to cant inwardly, this tendency is overcome when the strip engages the surface of the socket 5 or other clamped device.

Irrespective of the angle at which the faces 7a and 7b are inclined with respect to the cam 17 it is preferable to bend the extremities of the flexible strip 7 outwardly in opposite directions as indicated at 7x, 7y to prevent the cam from undesired twisting, or lateral movement, as the screw 13 is turned.

From the foregoing, it is apparent that the present invention provides a simple, inexpensive and trouble-free clamp and one wherein the adjusting mechanism is accessible from the top of the installation, whereby replacement of the clamped device may be effected without disturbing the set-up of other nearby units.

What is claimed is:

1. Apparatus of the type described comprising, in combination, a base, a clamping member comprising a flexible strip adapted to be supported on

said base and to be circumferentially disposed about the object to be clamped, cam means operatively connecting the ends of said flexible strip, and means extending in a direction perpendicular to said base between said ends of said flexible strip and accessible from a point along the said perpendicular for adjusting said cam means, whereby to apply a clamping force to said object through said flexible strip.

10 2. A clamp comprising the combination with a flexible strip having a body portion adapted to encircle the object to be clamped and having outwardly extending oppositely located spaced end portions, of a cam spanning said space and adapted to bear against the said end portions of said strip, and means cooperatively associated with said cam and extending in a direction parallel to said body portion of said strip for applying a clamping force to said object.

15 3. A clamp comprising the combination with a flexible strip adapted to encircle the object to be clamped and having outwardly extending oppositely located spaced end portions, of a V-shape cam spanning said space and adapted to bear against the said end portions of said strip, and means comprising a screw disposed between said end portions and in contact with the central portion of said V, for actuating said cam.

20 4. The invention as set forth in claim 3 and 30 wherein the surfaces of said end portions of said strip are inclined at substantially the same angle as the inclined surfaces of said V-shape cam.

HARLIN A. BRELSFORD.
